UNITED STATES PATENT OFFICE.

JOHN YIRIKIAN, OF NEW YORK, N. Y.

VERTICALLY-SPLIT ATTACHMENT FOR REMOVABLE DENTAL BRIDGEWORK.

Application filed March 1, 1921. Serial No. 448,847.

To all whom it may concern:

Be it known that I, JOHN YIRIKIAN, a citizen of the United States, residing at New York, in the county of New York and State of New York, have invented certain new and useful Improved Vertically-Split Attachments for Removable Dental Bridge-work, of which the following is a specification.

10 My invention relates to an improved vertically split attachment for removable dental bridge work and has for its object to fasten a removable dental bridge securely in the mouth by frictional engagement with an anchoring abutment or abutments.

15 A further object of my invention is to provide an attachment split vertically to vary the frictional engagement as desired but in such a manner that there is no tendency to break out the side of the inlay in which it is anchored.

20 A further object of my invention is to provide an attachment in which the frictional engagement with the anchoring abutment may be increased or decreased throughout the entire length of the attachment.

25 Other and further objects of my invention will be apparent from the following description and from the accompanying drawings 30 in which—

Figures 1 and 1^A illustrate in perspective the improved vertically split attachment;

35 Figures 2 and 2^A the split tubes in which the anchoring members of the attachments are adapted to fit;

Figures 3 and 3^A the inlays for the abutment members in which the split tubes are secured;

40 Figures 4 and 4^A a molar and a bicuspid, respectively, prepared to serve as anchoring abutments and showing inlays, split tubes, and attachments in place;

45 Figure 5 an artificial bicuspid and molar adapted to replace corresponding natural teeth;

Figure 6 a bridge on which the artificial teeth of Figure 5 are adapted to be mounted and provided with the improved vertically split attachments;

Figure 7 a portion of the jaw with missing teeth and with the abutment teeth prepared to receive the removable bridge work;

Figure 8 the portion of the jaw illustrated in Figure 7 with the removable bridge work in place;

Figure 9 illustrative embodiments A, B, C, D, E, and F of forms of attachments; and

Figure 10 an enlarged view of an attachment showing the manner in which the anchoring member thereof is split.

60

It is the practice in high-class mechanical dentistry to secure to natural teeth by frictionally engaging attachments a removable bridge carrying one or more artificial teeth. One form of such attachments is shown in 65 my Patent No. 1,218,083, granted March 6, 1917 for cone shaped removable bridge split attachment. This old form of attachment, however, is in two pieces and has the disadvantages incident to such structures. In the 70 present invention, the supporting member secured to the bridge is solid and although the anchoring member is split it is secured to or made integral with the supporting member so that the attachment has the advantages 75 of a unitary structure. There thus

is no danger of solder or of gold entering the split while the bridge is being made, and although the semi-solid construction enables the frictional contact of the anchoring member to be varied, the location and direction of the split minimizes the danger of breaking the anchoring abutment, the inlay, or the attachment itself.

75 In the drawings, reference character 1 indicates the supporting member of the attachment to which is secured or made integral therewith the anchoring member 2 provided

with a split 3 which preferably extends substantially vertically the entire length of the 80 anchoring member. It will be noted that the split is in the plane of the supporting member and thus at right angles to the outer edge and weakest part of the inlay 4. If the split was parallel to the outer edge of the inlay it would tend to break the inlay along that edge when the split was opened. With the split at right angles to the outside edge and parallel to the sides of the tooth, when the split is opened any force exerted is toward the sides of the inlay protected by the outer covering of the tooth.

85 It also will be obvious that if the split extends from top to bottom of the anchoring member, the anchoring member will engage throughout its 90 length with its split tube 6 in socket 5 of the inlay and give a maximum frictional surface for retaining the anchoring member in place against accidental displacement.

95 Inlay 4 is secured in abutments 7, which 100

usually are natural teeth, in any desired manner.

The supporting members 1 of the attachments preferably are secured to the support 5 or bridge 8 on which is mounted the artificial teeth 9.

It is obvious that one or more artificial teeth may be secured in this manner and that the attachments may be of any desired form 10 and shape both as to the supporting members and the anchoring members. Illustrative forms and shapes, which are not, however, intended to include all possible forms and shapes, are shown in Figure 9 of the 15 drawings.

Many modifications of my invention will be apparent to those skilled in the art without departing therefrom or from the scope of the claims, my invention not being limited to the particular embodiments chosen for purposes of illustration, but comprising an improved vertically split attachment for a removable bridge work adapted to hold the bridge firmly in place by adjustable frictional engagement with an abutment or abutments and without danger of breaking.

What I claim and desire to secure by Letters Patent is:

1. An attachment for removable bridge work comprising a solid supporting member 30 having a substantially vertical portion, and a substantially vertical anchoring member secured to said vertical portion of the sup-

porting member and adapted to fit within an inlay of an anchoring abutment, said anchoring member being provided with a substantially vertical split extending entirely through the member from top to bottom in the plane of the supporting member and at right angles to the outer edge of the inlay 40 whereby it is adapted to engage the inlay in which it is adapted to fit with an adjustable frictional engagement without danger of breaking any of the cooperating parts.

2. An attachment for removable bridge work 45 comprising a solid supporting member, and an elongated parallel anchoring member secured to said supporting member and split substantially vertically in the plane of said supporting member.

3. An attachment for removable bridge work comprising a solid supporting member, and an elongated parallel anchoring member secured to said supporting member and split substantially vertically from top to bottom.

4. A removable bridge attachment comprising an inlay with a vertical recess and a supporting member of two vertical parallel parts one of which is split vertically and the other of which is bent at right angles 55 to be secured to the bridge.

In testimony that I claim the foregoing, I have hereunto set my hand this 23rd day of February, 1921.

JOHN YIRIKIAN.
